James W. Rockhill INVENTOR

BY Chapin & Denny

HIS ATTORNEYS.

UNITED STATES PATENT OFFICE.

JAMES W. ROCKHILL, OF FORT WAYNE, INDIANA, ASSIGNOR TO EDWARD W. ROCKHILL AND MARY R. ROCKHILL, OF ALLEN COUNTY, INDIANA.

FENCE-POST.

SPECIFICATION forming part of Letters Patent No. 613,478, dated November 1, 1898.

Application filed March 3, 1898. Serial No. 672,350. (No model.)

To all whom it may concern:

Be it known that I, JAMES W. ROCKHILL, a citizen of the United States, residing at Fort Wayne, in the county of Allen, in the State of Indiana, have invented certain new and useful Improvements in Fence-Posts; and I do hereby declare that the following is a full, clear, and exact description of the invention, which will enable others skilled in the art to 10 which it appertains to make and use the same, reference being had to the accompanying drawings, which form part of this specification.

My invention relates to improvements in 15 artificial-stone posts.

The object of my invention is to provide a fence-post of economical construction, great strength, non - corrosive, practically indestructible, and adapted for use with any kind 20 of fence, whether of boards, pickets, wires, or rails, without the use of holding-bolts passing through said posts, as is usual in concrete posts.

My invention consists of an artificial-stone 25 post, composed of Portland cement or its equivalent with a proper proportion of concrete, so formed or molded that when dry it will be as hard and practically as durable as stone, the said post being provided with longitudinal strengthening - wires embedded 30 therein and an upright wooden bar secured to said post and provided with means for maintaining said bar in position.

In the accompanying drawings, in which 35 similar reference - numerals indicate like parts, Figure 1 is a vertical central sectional view, transverse to the longitudinal line of the fence, of the improved form of my fence-post in position in the ground, showing the central 40 strengthening-wire and the upright wooden bar 3. Fig. 2 is a detail cross-sectional view of the post, showing the means of securing the upright wooden bar in position.

The post 1, of any desired form and dimension, preferably rectangular, consists of a continuous non-sectional concrete body and is formed by a composition whose ingredients are Portland cement or its equivalent in a proper concrete to be inserted in the earth 5.

50 My improved fence-post thus formed has a longitudinal central wire rod 2, of a suitable size,

properly embedded therein to strengthen the same. Additional strengthening-wires may be embedded in the concrete in parallel relation to the central wire 2, though such additional wires are not essential to my improvement. The bar 3 may be of the same length as the post 1 or not, as desired. In the view Fig. 1 the bar 3 only extends to the soil; but, if desired, it may be extended below the soil-surface to any depth, in which construction the lower end of the post is enlarged and the bar embedded therein the better to protect it from moisture and decay. A series of horizontal wires 4 are secured to the post, so arranged as to pass around the said central wire rod 2, as shown in Fig. 2, with their free ends protruding from the front face of the post and adapted to firmly embrace the upright bar 3, which is thereby secured to the 60 front face of the post. The free ends of the wires are then united by a twist, as shown.

It is obvious that a fence-post thus constructed is cheap, strong, and practically indestructible, and is adapted for use either in 65 making and supporting a board, wire, rail, or picket fence without the use of any holding-bolts, and is very durable.

Having thus described my invention and the manner of employing the same, what I 70 claim as new, and desire to secure by Letters Patent, is—

A fence-post consisting of a concrete body formed of the specified ingredients, having an embedded strengthening-wire rod, extending 75 the length thereof, and provided with a series of wire loops passing around said rod and having their free ends protruding from the front face of said post, and adapted to firmly embrace and secure an upright wooden bar, 80 in combination with a wooden bar 3 secured in position by the tie end of said loops as shown and to which the fence-sections are secured.

Signed by me, at Fort Wayne, Allen county, 85 State of Indiana, this 26th day of February, A. D. 1898.

JAMES W. ROCKHILL.
